UNITED STATES PATENT OFFICE.

ROBERT S. PEELLE, OF NEW YORK, N. Y., ASSIGNOR TO THE PEELLE COMPANY, OF BROOKLYN, NEW YORK, A CORPORATION OF NEW YORK.

CONTROLLING MECHANISM FOR ELEVATOR DOORS.

1,410,271.

Specification of Letters Patent. Patented Mar. 21, 1922.

Application filed August 2, 1919. Serial No. 314,827.

To all whom it may concern:

Be it known that I, ROBERT S. PEELLE, a citizen of the United States, residing at Hollis, in the borough of Queens, city of New York, county of Queens, and State of New York, have invented certain new and useful Improvements in Controlling Mechanisms for Elevator Doors, of which the following is a specification, reference being had therein to the accompanying drawings, which form a part thereof.

My invention relates to controlling mechanisms for elevator doors, and more particularly to controlling mechanisms for elevator doors of the full automatic type, the term "full automatic" in this art referring to a door which is both opened and closed without the application of manual power thereto.

In an elevator door made in accordance with my invention, I employ an electric motor actuating a winch, the cable from which is operatively connected with each door in a shaft in a manner to permit the opening of any door by a controller located in the car.

My invention is particularly applicable to elevator doors wherein the door structure is such that upon the release of a latch, the door will either automatically open or automatically close, this normal tendency of the door being controlled by the actuating mechanism of my invention, so as to place both the opening and the closing movement of the door under the control of the operator through the controller in the car.

It is essential, in connection with doors of the type to which my invention relates, to provide each door with an individual locking mechanism in order that the actuating mechanism common to all of the doors will be operative only to permit the opening of that door at which a car may be, this latch mechanism either being operated manually or by a mechanism carried by the car, preferably the latter.

In addition to thus providing for the power opening and closing of the several doors in a shaft, I provide, in connection with the door actuating mechanism, a suitable mechanism whereby, with the initial opening movement of the door, the electrical circuit controlling the application of power

to the car will be made or broken to prevent movement of the car after the door has once been opened, and permitting the application of power to the car only when a door has been fully closed. This mechanism is actuated through the same mechanisms controlling the opening and closing movement of the doors, and while it is operatively connected with the doors so as to move in synchronism therewith, it nevertheless does not have any operative effect upon the doors, being dependent solely upon said door actuating mechanism for its functioning.

When the circuits to the motor forming a part of the door actuating mechanism, are open, said door actuating mechanism will be locked so as to prevent the forcing of any door, this lock also being utilized to prevent any tendency of such an overrunning of the motor as would tend to impart movement to any door in excess of that required to fully close same.

In addition to the characteristics above referred to, I provide, in addition to the controller for the door actuating mechanism within the car, automatically acting switches having the two-fold function of preventing the application of power to the motor of the door actuating mechanism, except under conditions required by the position of the door, while at the same time limiting the duration of the application of power to a door to that interval required to either fully open or fully close same.

The controller of the circuits to the door actuating mechanism, which is arranged in the car, is so constructed that by a single movement all of the electrical conditions about said door actuating mechanism will be properly and simultaneously established.

While the application of power to the car will be prevented substantially instantly with the initial opening movement of a door, and will be permitted only with the full closure thereof, and while the supplemental switch mechanism above referred to will permit power to be applied to the door to impart movement thereto only in that direction which the condition of the door will permit, nevertheless a door may be fully opened and closed irrespective of the con-

- trol of the power for actuating the car, and the power for opening and closing a door may be cut off when the door is either partially opened or partially closed, and 5 thereafter applied thereto, to either fully open or fully close the door, the supplemental switch mechanism above referred to being operative only when the door is either fully opened or fully closed.
- 10 The controller within the car is so constructed and arranged that immediately upon its release by the operator, the various circuits to the door actuating mechanism will be instantly interrupted, thus permitting movement of a door to be instantly arrested by merely releasing said controller, thus imparting to the device a great factor of safety.
- 15 The invention consists primarily in a controlling mechanism for elevator doors embodying therein a plurality of vertically sliding doors in a shaft, an electric motor, a winch actuated thereby, a flexible connection passing about said winch and operatively connected with each door in a shaft, a controller for the circuits to said motor arranged within a car, and a limit switch mechanism whereby the operative effect of said controller will be determined by the position of any door in a shaft; and in such other novel features of construction and combination of parts as are hereinafter set forth and described, and more particularly pointed out in the claims hereto appended.
- 20 Referring to the drawings,
- Fig. 1 is a view showing a portion of an elevator shaft showing two doors therein, and a controlling mechanism therefor embodying my invention;
- 25 Fig. 2 is a detail view of the clutch mechanism for preventing excess movement of the motor;
- 30 Fig. 3 is a side elevation of one form of controller;
- 35 Fig. 4 is an end elevation thereof; and
- 40 Fig. 5 is a diagrammatic view of the wiring of the controlling mechanism.
- 45 Like letters refer to like parts throughout the several views.
- 50 In the embodiment of my invention shown in the drawings, I have indicated at A a portion of an elevator shaft having mounted therein two door structures of a type in which the sections, in opening and closing 55 the doors, have simultaneous movement in opposite directions in the same vertical plane. The construction of each of the doors shown is the same as the other, and duplicate reference letters are therefore used in conjunction therewith. Each of the doors 60 comprises an upper section *a* and a lower section *b* connected by the cable or other flexible connection *c* passing over the pulleys *c'*. The lower section *b* is provided with a 65 hanger bar *b'* projecting beyond each side

of the section *b*. The detailed construction of the doors is immaterial to the present invention, and is therefore not shown in the drawings or herein described.

The section *b*, in the type of door shown, 70 overbalances the section *a* so that when the latch mechanism of the door is released, which mechanism is shown conventionally at *d*, there is a normal tendency of the door to open automatically.

75 In connection with said doors, I provide a door actuating mechanism including therein a reversible electric motor *e* and a winch *f* driven therefrom by means of the worm gear shaft *f'* and gear *f''*. Extending about 80 the winch *f* is a flexible strip, cable, or other connection *g* having branches *g'* and *g''* passing about the pulleys *g'* and *g''* respectively and operatively connected with each of the doors in a shaft by being passed through an 85 opening in the hanger bar *b'* in which said extension cables *g'* and *g''* are free to slide. This construction is to permit the opening of any door in a shaft upon the actuation of the motor *e*, the strips *g'* and *g''* being 90 capable of movement with a door to be opened and of movement independently of all the other doors in a shaft which remain closed. The extensions *g'* and *g''* carry, 95 adjacent and below each hanger bar *b'*, a block *h* adapted to normally engage said hanger bar when the door is closed, to have movement therewith as the door is opened, and to impart movement to a door during the closing operation.

100 The extensions *g'* and *g''* each have a weight, as *i*, at the lower end thereof to maintain these extensions taut.

After passing about the winch *f*, the flexible strip or cable *g* passes to a sliding weight 105 *j* mounted in suitable guides *j'*, said guides adjacent the bottom thereof supporting a make and break mechanism *j''* controlling the circuit to the car actuating means. This weight, by this construction, moves in sync- 110 chronism with any door being opened and closed, the load of the weight, however, being sustained by the winch *f*, thus relieving the doors of any influence from this weight.

In Fig. 1 of the drawings, I have shown 115 the controlling mechanism for the car actuating circuit, merely conventionally, since the details of this construction form no part of my present invention. It is desirable, however, to control the application of power to a car 120 in accordance with the movement of a door. The weight *j* in addition to controlling the car actuating circuit, also serves to take up slack resulting from the actuation of the winch *f*. I have found it desirable, how- 125 ever, to utilize this take-up mechanism for controlling said main actuating circuit, but do not desire to make this feature of the mechanism essential to the invention considered in its broader aspects.

As a consequence of the mechanism above described, it is apparent that the actuation of the motor e is essential to both the opening and the closing of a door in a shaft, the extent of such movements of the doors being controlled by the duration of the operation of said motor. To limit the operative effect of the motor to open or close a door to the extent required to either fully open or fully close it, I provide means adapted to set substantially simultaneously with the completion of the closing movement, and with the completion of the opening movement of the door, which will interrupt the circuit to the motor e , thus relieving the operator from any necessity for controlling the duration of the movement of the door through the controller in the car.

This automatic circuit interrupter may be aptly described as a limit switch mechanism. In addition to thus interrupting the circuit, this limit switch mechanism has the further characteristic that when a door is either fully opened or fully closed, it will prevent application of power to the motor e except to actuate the winch f in one direction only, which direction is defined by the position of the door. As will more fully appear hereinafter, this mechanism will permit a partially opened door to be moved in either direction without requiring movement thereof to the fully opened or fully closed position.

In conjunction with the limit switch mechanism, I provide an automatically acting brake operative upon the motor e , which, upon the interruption of the circuit to the motor e , will be automatically set to prevent possible overrunning of the motor after the interruption of the circuit, this braking mechanism, however, being released substantially simultaneously with the closing of the circuit to the motor e , and remaining in this condition so long as the circuit to the motor e remains closed.

While the limit switch mechanism operates entirely independently of the controller switches in the car, the actuation of the brake mechanism above referred to is controlled by said controller switches.

In describing said limit switch mechanism said brake mechanism and said controller mechanism, I will do so in conjunction with the circuits employed in connection with the door actuating mechanism, which circuit is indicated diagrammatically in Fig. 5.

Carried by the car B is a controller switch mechanism C consisting of a frame k having upon opposite sides thereof, similar spring contact members k' , k^2 , k^3 , k^4 , k^5 and k^6 . The contact members k' to k^6 upon one side of said frame are adapted to close the various circuits incidental to the opening of a door, while the corresponding contacts upon the other side of the frame are adapted to close the circuits for the closing of a door.

Pivotedly mounted between the two sets of contacts above referred to, is a bridge contact member m having contacts m' of electro-conductive material, adapted to simultaneously engage all of the contacts upon either side thereof according to the direction of movement of the member m .

The shaft of said member m is provided with a crank arm m^2 which is acted upon by a spring m^3 so that normally the contact m will be positioned centrally between the two sets of contacts k' to k^6 , and out of electrical connection with either of them. By this construction it is apparent that to ensure a continued movement of a door in either direction, it is necessary for the operator to maintain the contacts m' in engagement with one set of contacts, since immediately that the operating handle m^4 for the member m is released, the various circuits will be instantly and automatically interrupted and thus prevent further movement of the car.

In the embodiment of the invention shown, two of the contacts, as k' and k^2 , will be electrically connected through the wires 1 and 2, to the main line wires 3 and 4 from the source of power for actuating the doors. Others of the contacts, as k^3 and k^4 , will be connected through the wires 5 and 6 with the field 7 of the motor e , while the remaining contacts k^5 and k^6 will be electrically connected through the wires 8 and 9 with the armature brushes. The corresponding contacts upon the opposite side of the member m will be connected respectively by the wires 1^a and 2^a with the source of power 3 and 4, by the wires 5^a and 6^a with the field of the motor, and by the wires 8^a and 9^a with the commutator brushes, there being this difference in the wiring of the two sets of spring contacts, that while the wires 8 and 9 will be connected respectively with the brushes e' and e^2 , the wires 8^a and 9^a will be connected respectively with the brushes e^2 and e' , thus reversing the direction of flow of the current in the armature with a resultant reversal of the direction of rotation of the motor. Hence the switch mechanism C in addition to its other functions, serves as a pole changer.

The limit switch mechanism comprises two switches n and o arranged upon a suitable switch board and spaced apart a distance substantially equal to the movement of a door from the fully opened to the fully closed position, or vice versa.

The switch mechanism n comprises fixed contacts n' and n^2 forming a gap in the wire 1, which gap is adapted to be enclosed by a bridge contact n^3 carried by an oscillatory lever n^4 acted upon by a spring n^5 to normally bring the contact n^3 in electrical connection with the contacts n' and n^2 . The switch mechanism o has contacts o' and o^2 130

similar to the contacts $n' - n^2$, a bridge contact o^3 similar to the contact n^3 and a lever o^4 and spring o^5 similar to the lever and spring $n^4 - n^5$. The contacts o' and o^2 form 5 a gap in the wire 1^a instead of in the wire 1. By this construction the circuits to both sets of contacts k' to k^6 will be automatically included in the circuit from the main line 3-4 when the working conditions about the 10 door actuating mechanism are such as to require this condition.

The lever arms $n^4 - o^4$ and the parts actuated thereby are oppositely set so that while movement of one of said levers in one direction will effect the closing of the circuit, 15 similar movement of the other lever will effect the opening of its circuit.

The flexible connection g passes through 20 both of the lever arms $n^4 - o^4$ and has secured thereto, intermediate said arms, contact balls or block $p - p'$ adapted respectively to co-operate with said levers upon a predetermined movement of the said connection g .

25 The brake mechanism above referred to comprises a disc q carried by and rotatable with the shaft f' . Pivotally mounted adjacent said disc, are brake shoes $q' - q^2$, one of which, q' , has pivotally mounted thereon a bell crank lever q^3 , one arm of which is connected by means of the adjustable link q^4 with the other shoe q^2 .

30 Mounted adjacent the disc q is a solenoid or other electromagnet r , the core of which is pivotally connected with said bell crank lever, said core being so set that upon the energizing of the magnet r , the bell crank lever q will be so oscillated as to release the 35 brake shoes q' and q^2 . Acting upon the bell crank lever q^3 is a spring r' having a normal tendency to set the brake shoes $q' - q^2$ upon the disc q .

The solenoid r is included, by means of the 40 terminal wires 10-11, in the circuit to the field 7, thus causing the release of the brake mechanism with any actuation of the controller switch C, irrespective of the purpose for which this switch may be used.

45 The operation of the herein described mechanism is substantially as follows:—

Assuming that the parts are in the position shown in Fig. 1 of the drawings, the various doors in a shaft will be closed, the 50 brake shoes $q' - q^2$ being set upon the disc q in a manner to prevent rotation of the winch f and thus serve to effectively lock all of the doors in a shaft, supplementing in this respect the individual locks d operative in connection with the several doors.

55 Under this condition it is impossible to open any door in a shaft except from the car B, the individual locks d preventing the opening of any door except that closing the 60 opening at the floor at which the car B is standing.

Assuming that the car ascends to the doorway toward the top of Fig. 1, and it is desired to open this door, when the car is brought to rest, the lock d will be released by a suitable mechanism on the car when the 70 type of lock shown in the drawings is used. Any other desired form of lock may be used, however, in lieu of that shown, my invention not relating to the form of individual lock employed.

75 When it is desired to open the door, the operator turns the contact member m so as to swing the contacts m' thereof to the right, as shown in Fig. 4, thus simultaneously engaging all of the contacts k' to k^6 upon that side of the frame k . At this time the switch mechanism n will be so set as to close the circuit through the wire 1, so that with the movement of the member m , the following results will occur simultaneously. The field 80 of the motor e will be energized, the current will pass to the motor armature, and the solenoid r will be energized to release the brake shoes q' and q^2 .

85 When the circuit is thus closed the winch 90 f will be driven by the motor in a manner to pay out the strip or cable g and its branches g' and g^2 , thus permitting that door, the lock d of which has been released, to open as a result of the descent of the 95 blocks h carried by the extensions g' and g^2 adjacent the hanger bar b' of that door. The blocks h adjacent the other doors will merely recede from their respective hanger bars, the doors being held in the closed position by their individual locks d .

95 With the paying out of the portion of the strip or cable g between the winch f and the several doors, that portion of said strip or cable g between the winch and the block j 100 will be taken up, thus simultaneously permitting the opening of a door, and raising the block j .

With the initial movement of said block j , the make and break mechanism j^2 will be 110 automatically actuated to prevent application of power to the car, thus preventing the car leaving the floor until the door has again been closed.

With the paying out of the strip or cable 115 g in the manner above referred to, the block p , will recede from the lever o^4 , thus permitting the actuation of the lever under the spring o^5 so as to close the gap in the line 120 1^a through the contacts o' , o^2 and o^3 , and include the opposite set of contacts k' to k^6 in the main circuit 3-4.

125 The opening movement of the door will continue so long as the operator holds the contact member m in the position heretofore referred to. If, however, the operator should release this contact member, the spring m^3 will instantly restore said member to a neutral position and thus interrupt the circuits to the field and the armature of the 130

motor, and to the solenoid r , thus causing the paying out of the cable g to instantly stop, any possible overrunning of the motor e being prevented by the automatic setting 5 of the brake members $q'—q^2$ under the influence of the spring r' .

Under this condition it will be observed that both switches $n—o$ are so set as to close the circuits through the wires 1 and 1^a respectively, thus permitting either set of contacts $k' to k^6$ to be used so that the door may be either opened or closed, as desired.

The automatic opening of all circuits in the door actuating mechanism is a great 15 factor of safety, it being possible for the operator to instantly arrest all movement of the doors by merely releasing the controller handle.

Assuming, however, that the operator continues to hold the member m in a position to close the circuits to effect the opening of a door, until the door is fully opened, the closing of the circuit through the wire 1^a will have no influence whatever in the functioning of the device. When the door approaches a fully open position, however, the ball or block p upon the strip or cable g will engage the lever n^4 , and with the completion of the opening movement of the door, oscillate said lever in a manner to separate the contacts n', n^2 and n^3 , and thus automatically open the circuits to the door actuating mechanism, independently of any action of the operator, or any movement of the contact member m . 35 Any movement of the winch f in excess of that required to fully open the door, is thus prevented.

While the opening of the door will result primarily because of the greater weight in 40 the section b than in the section a , the speed of movement will be controlled entirely by the motor e through the winch f , the worm gear drive of said winch not only serving as a speed reducing transmission, but also as 45 a lock which will relieve the door structure from any counter-balancing effect from the weight j . Of course it is understood that the strip or cable g is passed several times about said winch.

50 When a door is fully opened, if an operator should move the contact m in the wrong direction, this will have absolutely no effect in the electrical conditions within a car, since the limit switch n will be maintained in a condition which will prevent the flow of the current to the motor e or solenoid r . Hence, if it be desired to close the door, it is necessary to throw the pivotal contact member m in the opposite direction or with 55 the contacts m' to the left, as shown in Fig. 4, thus bridging the contacts $k' to k^6$ on the other side of the frame k , and closing the 60 circuits to the two brushes $e'—e^2$ but with the opposite polarity to the motor armature, 65 and to the solenoid r , with a resultant re-

lease of the brake shoes $q'—q^2$ and the actuation of the motor e and winch f , but in the reverse direction.

As a result of this reversal of the direction of rotation of the winch f , it will pay 70 out the strip or cable g between it and the weight j , while a lifting action upon the open door will be exerted by the blocks h upon the extensions $g'—g^2$.

With the initial movement of the door, 75 the block p will recede from the lever n^4 , thus permitting the spring n^5 to actuate said lever in a manner to again close the circuit through the wire 1 .

As the door approaches the closed position, the block p' will engage the lever n^4 , and actuate said lever upon the completion of said closing movement, in a manner to interrupt the circuit through the wire 1^a and thus interrupt the various circuits to the 85 door actuating mechanism, and automatically arrest further movement of the doors.

The weight j will take up all slack in the cable g as it is created by the winch f , said weight, as the doors approach their closing 90 movement, actuating the make and break mechanism f in a manner to close the circuit to the car actuating mechanism and thus permit power to be applied to the car for movement in either direction.

95 By the foregoing it will be observed that any door in a shaft may be opened and closed by means of a single door actuating mechanism; but that when a door is opened this mechanism can be operated only in a 100 manner to close the door; that when a door is closed it may be actuated only in a manner to open the door; and that when a door is partially opened, it may be actuated either to fully open or fully close it. It will also 105 be observed that the automatic brake mechanism operative upon the motor e , and the power transmission mechanism connecting the motor e with the winch f , will not only effectively prevent overrunning of the motor 110 and of the winch upon the interruption of the circuit to the former, but will serve to effectively lock the doors when in the closed position and prevent the forcible opening thereof from the floor side of the door opening. 115

The mechanism shown in the accompanying drawings, I have found highly satisfactory in actual use, but there may be many variations thereof securing the desired operative effects, without departing from the spirit and scope of the invention. It is, therefore, not my intention to limit the invention to the precise details of construction shown in the accompanying drawings.

120 Having described the invention, what I claim as new and desire to have protected by Letters Patent, is:—

1. A controlling mechanism for elevator doors embodying therein a plurality of ver- 130

tically sliding doors in a shaft, an electric motor, a winch actuated thereby, a flexible connection passing about said winch, means carried thereby adjacent each door in a shaft, and adapted to normally engage its door when in the closed position, and to have movement toward and from this position with the actuation of said winch in opposite directions, whereby all doors in a shaft will be normally held against opening movement by said means, said flexible connection and said winch, and any door in a shaft may be opened with the movement of said means away from, and will be closed by a return of said means toward, its normal position, a controller for the circuit to said motor arranged within a car, and a limit switch mechanism whereby the operative effect of said controller will be determined by the position of any door in a shaft.

2. A controlling mechanism for elevator doors embodying therein a vertically sliding door in a shaft, an electric motor, a winch actuated thereby, a flexible connection passing about said winch, means carried thereby adapted to normally engage said door when in the closed position, and to have movement toward and from this position with the actuation of said winch in opposite directions, whereby said door will be normally held against opening movement by said means, said flexible connection and said winch, and said door may be opened with the movement of said means away from, and will be closed by a return movement of said means toward, its normal position, a controller for the circuit to said motor, and means adapted to automatically interrupt the circuit to said motor when said door reaches the fully opened, and the fully closed, position.

3. A controlling mechanism for elevator doors embodying therein a vertically sliding door in a shaft, an electric motor, a winch actuated thereby, a flexible connection passing about said winch, means carried thereby adapted to normally engage said door when in the closed position, and to have movement toward and from this position with the actuation of said winch in opposite directions, whereby said door will be normally held against opening movement by said means, said flexible connection and said winch, and said door may be opened with the movement of said means away from, and will be closed by a return movement of said means toward, its normal position, a controller for the circuit to said motor, means adapted to automatically interrupt the circuit to said motor when said door reaches the fully opened, and the fully closed, position, a brake mechanism, means tending to normally set said brake mechanism to prevent movement of said motor and said winch, and an electromagnet operative to relieve

said brake mechanism, said magnet being included in a circuit from said controller, whereby said brake mechanism will be released only while the circuit to said motor is closed.

4. A controlling mechanism for elevator doors embodying therein a vertically sliding door in a shaft, an electric motor, a winch, a speed reducing transmission mechanism between said motor and said winch including therein a shaft, a brake drum carried by said shaft, brake shoes pivotally mounted adjacent said drum, a bell crank lever mounted on one of said brake shoes, a link connecting one arm of said lever with the other of said brake shoes, a spring acting to normally set said brake shoes upon said drum, a solenoid having the core thereof connected with the other arm of said lever, a flexible connection passing about said winch, means carried thereby adapted to normally engage said door when in the closed position, and to have movement toward and from this position with the actuation of said winch in opposite directions, whereby said door will be normally held against opening movement by said means, said flexible connection and said winch, and said door may be opened with the movement of said means away from, and will be closed by a return movement of said means toward, its normal position and a controller adapted to simultaneously open or close electrical circuits to said motor and said solenoid respectively, whereby, when said circuits are closed, said brake shoes will be disengaged from, and when said circuits are interrupted, said brake shoes will be instantly set upon, said drum.

5. A controlling mechanism for elevator doors embodying therein a plurality of vertically sliding doors in a shaft, an electric motor, a winch actuated thereby, a flexible connection passing about said winch, means carried thereby adjacent each door in a shaft, and adapted to normally engage its door when in the closed position, and to have movement toward and from this position with the actuation of said winch in opposite directions, whereby all doors in a shaft will be normally held against opening movement by said means, said flexible connection and said winch, and any door in a shaft may be opened with the movement of said means away from, and will be closed by a return of said means toward, its normal position, a controller for the circuit to said motor arranged within a car, a limit switch mechanism whereby the operative effect of said controller will be determined by the position of any door in a shaft, a brake mechanism, means tending to normally set said brake mechanism to prevent movement of said motor and said winch, and an electromagnet operative to relieve said brake mech-

anism, said magnet being included in a circuit from said controller, whereby said brake mechanism will be released only while the circuit to said motor is closed.

6. A controlling mechanism for elevator doors embodying therein a plurality of vertically sliding doors in a shaft, an electric motor, a winch, a speed reducing transmission mechanism between said motor and said 10 winch including therein a shaft, a brake drum carried by said shaft, brake shoes pivotally mounted adjacent said drum, a bell crank lever mounted on one of said brake shoes, a link connecting one arm of said 15 lever with the other of said brake shoes, a spring acting to normally set said brake shoes upon said drum, a solenoid having the core thereof connected with the other arm of said lever, a flexible connection passing 20 about said winch, means carried thereby adjacent each door in a shaft, and adapted to normally engage its door when in the closed position, and to have movement toward and from this position with the actuation of said 25 winch in opposite directions, whereby all doors in a shaft will be normally held against opening movement by said means, said flexible connection and said winch, and any door in a shaft may be opened with the movement of said means away from, and 30 closed by a return of said means toward, its normal position, a controller arranged with in a car and adapted to simultaneously open and close electrical circuits to said motor and 35 said solenoid respectively, whereby, when said circuits are closed, said brake shoes will be disengaged from, and when said circuits are interrupted, said brake shoes will be instantly set upon, said drum, and means adapted 40 to automatically interrupt the circuits to said motor and to said solenoid when any door reaches a fully opened, and a fully closed, position.

7. A controlling mechanism for elevator doors embodying therein a vertically sliding door in a shaft, a reversible electric motor, a winch actuated thereby, a flexible connection passing about said winch, means carried thereby adapted to normally engage said 45 door when in the closed position, and to have movement toward and from this position with the actuation of said winch in opposite directions, whereby said door will be normally held against opening movement by 50 said means, said flexible connection and said winch, and said door may be opened with the movement of said means away from, and will be closed by a return movement of said 55 means toward, its normal position, a controller embodying therein a pole changing switch mechanism for the circuit to said motor, and means adapted to automatically 60 interrupt the circuit to said motor when said door reaches the fully opened, and the fully closed, position.

8. A controlling mechanism for elevator doors embodying therein a vertically sliding door in a shaft, a reversible electric motor, a winch actuated thereby, a flexible connection passing about said winch, means carried 70 thereby adapted to normally engage said door when in the closed position, and to have movement toward and from this position with the actuation of said winch in opposite directions, whereby said door will be normally held against opening movement by 75 said means, said flexible connection and said winch, and said door may be opened with the movement of said means away from, and will be closed by a return movement of said 80 means toward, its normal position, a controller for the circuit to said motor, embodying therein electrical contacts in circuit with the line, other electrical contacts in circuit with the motor, and movable contacts adapted respectively to close the circuits through said 85 contacts, and means adapted to automatically interrupt the circuit to said motor when said door reaches the fully opened, and 90 the fully closed, position.

9. A controlling mechanism for elevator doors embodying therein a plurality of vertically sliding doors in a shaft, a reversible electric motor, a winch actuated thereby, a flexible connection passing about said winch, 95 means carried thereby adjacent each door in a shaft, and adapted to normally engage its door when in the closed position, and to have movement toward and from this position with the actuation of said winch in opposite 100 directions, whereby all doors in a shaft will be normally held against opening movement by said means, said flexible connection and said winch, and any door in a shaft may be 105 opened with the movement of said means away from, and will be closed by a return of said means toward, its normal position, a controller embodying therein a pole changing switch mechanism for the circuit to said 110 motor, and means adapted to automatically interrupt the circuit to said motor when said door reaches the fully opened, and the fully closed, position.

10. A controlling mechanism for elevator doors embodying therein a plurality of vertically sliding doors in a shaft, a reversible electric motor, a winch actuated thereby, a flexible connection passing about said winch, means carried thereby adjacent each door in a shaft, and adapted to normally engage its 115 door when in the closed position, and to have movement toward and from this position with the actuation of said winch in opposite directions, whereby all doors in a shaft will be normally held against opening movement 120 by said means, said flexible connection and said winch, and any door in a shaft may be opened with the movement of said means away from, and will be closed by a return of 125 said means toward, its normal position, a 130

controller for the circuit to said motor, embodying therein electrical contacts in circuit with the line, other electrical contacts in circuit with the motor, and movable contacts adapted respectively to close the circuits through said contacts, and means adapted to automatically interrupt the circuit to said motor when said door reaches the fully opened, and the fully closed, position.

11. A controlling mechanism for elevator doors embodying therein a plurality of vertically sliding doors in a shaft, an electric motor, a winch actuated thereby, a flexible connection passing about said winch, means carried thereby adjacent each door in a shaft, and adapted to normally engage its door when in the closed position, and to have movement toward and from this position with the actuation of said winch in opposite directions, whereby all doors in a shaft will be normally held against opening movement by said means, said flexible connection and said winch, and any door in a shaft may be opened with the movement of said means away from, and will be closed by a return of said means toward, its normal position, a controller for the circuit to said motor arranged within a car, a limit switch mechanism whereby the operative effect of said controller will be determined by the position of any door in a shaft, and means whereby the circuit from which power to move the car is derived, will be automatically interrupted with the actuation of said winch to open a door, and will be automatically restored upon the completion of the actuation of said winch to close the door.

12. A controlling mechanism for elevator doors embodying therein a plurality of vertically sliding doors in a shaft, an electric motor, a winch actuated thereby, a flexible connection passing about said winch, means carried thereby adjacent each door in a shaft, and adapted to normally engage its door when in the closed position, and to have movement toward and from this position with the actuation of said winch in opposite directions, whereby all doors in a shaft will be normally held against opening movement by said means, said flexible connection and said winch, and any door in a shaft may be opened with the movement of said means away from, and will be closed by a return of said means toward, its normal position, a controller for the circuit to said motor arranged within a car, a limit switch mechanism whereby the operative effect of said controller will be determined by the position of any door in a shaft, a make and break mechanism arranged in the circuit from which power to move the car is derived, and a sliding weight connected with the end of said flexible connection after it is passed about said winch, whereby said weight will

be caused to actuate said make and break mechanism to interrupt the circuit substantially simultaneously with the initial opening movement of the door under the control of said winch and said motor, and will close said circuit substantially simultaneously with the completion of said closing movement.

13. A controlling mechanism for elevator doors embodying therein a vertically sliding door in a shaft, an electric motor, a winch actuated thereby, a flexible connection passing about said winch, means carried thereby adapted to normally engage said door when in the closed position, and to have movement toward and from this position with the actuation of said winch in opposite directions, whereby said door will be normally held against opening movement by said means, said flexible connection and said winch, and said door may be opened with the movement of said means away from, and will be closed by a return movement of said means toward, its normal position, a controller for the circuit to said motor, means adapted to automatically interrupt the circuit to said motor when said door reaches the fully opened, and the fully closed, position, and means adapted to automatically position said controller so as to interrupt the circuit to said motor, whereby, to ensure a continued movement of the door, the operator must hold said controller in the operative relation.

14. A controlling mechanism for elevator doors embodying therein a vertically sliding door in a shaft, an electric motor, a winch actuated thereby, a flexible connection passing about said winch, means carried thereby adapted to normally engage said door when in the closed position, and to have movement toward and from this position with the actuation of said winch in opposite directions, whereby said door will be normally held against opening movement by said means, said flexible connection and said winch, and said door may be opened with the movement of said means away from, and will be closed by a return movement of said means toward, its normal position, a controller for the circuit to said motor embodying therein movable contacts, fixed contacts adapted to be selectively engaged thereby, operating means whereby said movable contacts may be caused to engage either set of fixed contacts, and a spring acting upon said operating means whereby said movable contacts will be normally held out of engagement with said fixed contacts, and means adapted to automatically interrupt the circuit to said motor when said door reaches the fully opened, and the fully closed, position.

15. A controlling mechanism for elevator doors embodying therein a plurality of ver-

- tically sliding doors in a shaft, an electric motor, a winch actuated thereby, a flexible connection passing about said winch, means carried thereby adjacent each door in a shaft, and adapted to normally engage its door when in the closed position, and to have movement toward and from this position with the actuation of said winch in opposite directions, whereby all doors in a shaft will be normally held against opening movement by said means, said flexible connection and said winch, and any door in a shaft may be opened with the movement of said means away from, and will be closed by a return of said means toward, its normal position, a controller for the circuit to said motor arranged within a car, and means whereby the circuit from which power to move the car is derived, will be automatically interrupted with the actuation of said winch to open a door, and will be automatically restored upon the completion of the actuation of said winch to close the door.
16. A controlling mechanism for elevator doors embodying therein a vertically sliding door in a shaft, an electric motor, a winch actuated thereby, a flexible connection passing about said winch, means carried thereby adapted to normally engage said door when in the closed position, and to have movement toward and from this position with the actuation of said winch in opposite directions, whereby said door will be normally held against opening movement by said means, said flexible connection and said winch, and said door may be opened with the movement of said means away from, and will be closed by a return movement of said means toward, its normal position, a controller for the circuit to said motor, a brake mechanism, means tending to normally set said brake mechanism to prevent movement of said motor and said winch, and an electromagnet operative to relieve said brake mechanism, said magnet being included in a circuit from said controller, whereby said brake mechanism will be released only while the circuit to said motor is closed.
17. A controlling mechanism for elevator doors embodying therein a vertically sliding door in a shaft, an electric motor, a winch actuated thereby, a flexible connection passing about said winch, means carried thereby adapted to normally engage said door when in the closed position, and to have movement toward and from this position with the actuation of said winch in opposite directions, whereby said door will be normally held against opening movement by said means, said flexible connection and said winch, and said door may be opened with the movement of said means away from, and will be closed by a return movement of said means toward, its normal position, a controller for the circuit to said motor embodying therein two sets of oppositely disposed fixed contacts, some contacts of each set being in circuit with the line, others being in circuit with the motor field winding, and others being in circuit with said motor, the last named contacts of one set being connected to poles of the motor armature opposite to similar contacts of the other set, two movable contacts adapted respectively to engage contacts of the same polarity in each set, and means whereby said movable contacts may be simultaneously engaged with the fixed contacts of either set, and means adapted to automatically interrupt the circuit to said motor when said door reaches the fully opened, and the fully closed, position.
18. A controlling mechanism for elevator doors embodying therein a vertically sliding door in a shaft, an electric motor, a winch actuated thereby, a flexible connection passing about said winch, means carried thereby, adapted to normally engage said door when in the closed position, and to have movement toward and from this position with the actuation of said winch in opposite directions, whereby said door will be normally held against opening movement by said means, said flexible connection and said winch, and said door may be opened with the movement of said means away from, and will be closed by a return movement of said means toward, its normal position, a controller for the circuit to said motor embodying therein two sets of oppositely disposed fixed contacts, some contacts of each set being in circuit with the line, others being in circuit with the motor field winding, and others being in circuit with said motor, the last named contacts of one set being connected to poles of the motor armature opposite to similar contacts of the other set, two movable contacts adapted respectively to engage contacts of the same polarity in each set, and means whereby said movable contacts may be simultaneously engaged with the fixed contacts of either set, and means adapted to automatically interrupt the circuit to said motor when said door reaches the fully opened, and the fully closed, position.
19. A controlling mechanism for elevator doors embodying therein a vertically sliding door in a shaft, an electric motor, a winch actuated thereby, a flexible connection passing about said winch, means carried thereby adapted to normally engage said door when in the closed position, and to have movement toward and from this position with the actuation of said winch in opposite directions, whereby said door will be normally held against opening movement by said means, said flexible connection and said winch, and said door may be opened with the movement of said means away from, and will be closed by a return movement of said means toward, its normal position, a brake mechanism,

means tending to normally set said brake mechanism to prevent movement of said motor and said winch, an electromagnet operative to relieve said brake mechanism, 5 and a controller for the circuit to said motor embodying therein two sets of oppositely disposed fixed contacts, some contacts of each set being in circuit with the line, others being in circuit with the motor field winding, others 10 being in circuit with said magnet, and others being in circuit with said motor, the last named contacts of one set being connected to poles of the motor armature opposite to similar contacts of the other set, two movable 15 contacts adapted respectively to engage contacts of the same polarity in each set, and means whereby said movable contacts may be simultaneously engaged with the fixed contacts of either set, and means adapted to 20 automatically interrupt the circuit to said motor when said door reaches the fully opened, and the fully closed, position.

20. A controlling mechanism for elevator doors embodying therein a vertically sliding door in a shaft, a reversible electric motor, a winch actuated thereby, a flexible connection passing about said winch, means carried thereby adapted to normally engage said door when in the closed position, and to have 25 movement toward and from this position with the actuation of said winch in opposite directions, whereby said door will be normally held against opening movement by 30

said means, said flexible connection and said winch, and said door may be opened with the 35 movement of said means away from, and will be closed by a return movement of said means toward, its normal position, a controller embodying therein a pole changing switch mechanism for the circuit to said 40 motor, two circuits of opposite polarity adapted to be selectively opened and closed by said controller, a make and break mechanism arranged in each of said circuits and oppositely disposed one to the other, each 45 of said mechanisms embodying a movable contact member, said contact members being spaced apart a distance equaling the full opening or closing movement of the door, and being movable in opposite directions to 50 make or break their respective circuits, and an impact member carried by said flexible connection between said movable contacts and adapted to alternately actuate same, whereby the circuit to said motor will be 55 automatically interrupted when said door reaches the fully opened, and the fully closed, position.

In witness whereof I have hereunto affixed my signature, in the presence of two subscribing witnesses, this 11th day of July, 1919.

ROBERT S. PEELLE.
